(57) CLAIM

The ornamental design for a massage head for a massage apparatus, as shown and described.

DESCRIPTION

FIG. 1 is a front perspective view of a massage head for a massage apparatus showing our new design;

FIG. 2 is a front elevational view thereof;

FIG. 3 is a back elevational view thereof;

FIG. 4 is a right elevational view thereof;

FIG. 5 is a left elevational view thereof;

FIG. 6 is a top plan view thereof; and,

FIG. 7 is a bottom plan view thereof.

The broken lines on claimed surfaces depict portions of the article and form no part of the claim.
